UNITED STATES PATENT OFFICE.

ERASTUS DE MOULIN, OF GREENVILLE, ILLINOIS.

TRICK WATER-GUN.

958,711.

Specification of Letters Patent. Patented May 17, 1910.

Application filed April 17, 1908. Serial No. 490,505.

To all whom it may concern:

Be it known that I, ERASTUS DE MOULIN, a citizen of the United States, residing at Greenville, in the county of Bond and State 5 of Illinois, have invented a new and useful Trick Water-Gun, of which the following is a specification.

This invention relates to trick guns of that general class especially designed for use 10 by members of lodges, fraternities, secret orders and similar organizations for initiating candidates.

The object of the invention is to provide means whereby an ordinary air rifle may be 15 converted into a water gun without the employment of additional operating mechanism and without altering the general appearance of the rifle.

A further object is to provide a trick gun 20 having a front and rear discharge, the rear discharge being extended through the gun sight.

Further objects and advantages will appear in the following description, it being 25 understood that various changes in form, proportions and minor details of construction may be resorted to within the scope of the appended claims.

In the accompanying drawings forming a 30 part of this specification:—Figure 1 is a longitudinal sectional view of a trick gun constructed in accordance with my invention showing the parts arranged to produce a forward discharge. Fig. 2 is a similar view of 35 the forward end of the gun showing the parts arranged to produce a rearward discharge. Fig. 3 is a transverse sectional view taken on the line 3—3 of Fig. 2. Fig. 4 is a transverse sectional view taken on the line 40 4—4 of Fig. 1. Fig. 5 is a longitudinal section through a portion of a modified form of gun.

Similar numerals of reference indicate 45 corresponding parts in all of the figures of the drawings.

The mechanism forming the subject matter of the present invention is designed for attachment to an air rifle, whereby the latter may be used as a water gun, and by way of 50 illustration is shown applied to a "Daisy" air rifle of the ordinary construction in which 5 designates the casing or housing, 6 the stock and 7 the false barrel.

Disposed within the false barrel is a trans- 55 verse partition 8 dividing the barrel into two compartments 9 and 10, the chamber 10 serv-

ing to receive water when a plunger 11 within the chamber 10 is retracted and the rifle used as a water gun.

The several parts above referred to are of 60 the usual construction, the present invention residing in the means employed for directing the rearward discharge through the gun sight.

Arranged within the false barrel 7 is a 65 true barrel 12 having its inner end threaded in an opening 13 in the partition 8 and its outer end projected longitudinally beyond the adjacent end of the false barrel 7 and provided with terminal threads 14 for engagement with a correspondingly threaded cap 15.

Mounted for rotation within the false barrel 7 is a valve 16 having a longitudinal bore, the walls of which are threaded for 75 engagement with the adjacent threaded end of the true barrel 12, said valve being provided with a laterally extending stop flange 17 and forming in effect a cap or closure for the chamber 9.

Secured in any suitable manner to the exterior wall of the false barrel 7 at a point adjacent the outer end thereof is a discharge barrel or tube 18, the mouth of which is extended in the direction of the plunger 80 11. The discharge barrel 18 constitutes a gun sight so that when the valve 16 is adjusted to produce a rearward discharge and the operator presses the trigger 19, the contents of the chamber will be discharged 85 through said sight in the face of the operator.

Formed in the threaded portion 20 of the true barrel is a port 21 adapted to register with a port or passage 22 formed in the 95 valve 16 and also with a port in the rear discharge barrel or sight 18. The valve 16 is so constructed that by rotating the latter in one direction the ports 21, 22 and 23 will register to permit a rearward discharge, and 100 when the valve is rotated in the opposite direction said valve will cut off communication between the ports 21 and 22 and thus permit the discharge of the fluid or other projectable substance through the forward 105 end of the true barrel, after the cap 15 is removed.

In operation the true barrel 12 and cap or valve 16 are removed by grasping the threaded end 14 of said true barrel and rotating 110 the same, after which a small quantity of water is introduced into the compartment 9

through the open end of the false barrel. The plunger 11 is then retracted by manipulating the lever 24, thus causing the fluid in the compartment 9 to enter the compartment 5 10 through the opening 13 in the partition 8 and partly fill said chamber. If a rearward discharge is desired, the valve 16 is rotated on the threads 20 until the passage 22 registers with the ports 21 and 23, respectively, 10 thus causing the water in the chamber 10 to pass through the true barrel 12 and ports 21 and 23 to the sight 18 where the liquid will be projected rearwardly in the face of the operator in the form of a fine stream. To 15 produce a forward discharge the cap 15 is removed from the threaded end 14 of the true barrel and the valve 16 rotated to cut off communication between the tube 18 of the true barrel 12 so that when the plunger 11 is 20 released the water in the chamber 10 will be forced longitudinally through the true barrel 12 and be ejected at the forward end of said true barrel. It will thus be seen that the valve 16 serves the dual function of a closure 25 for the chamber 9 and as a means for controlling the direction of flight of the projectable substance through the discharge passages of the gun. It will also be noted that the rearward discharge being extended 30 through the gun sight is hidden from the view of the operator so that the gun has the appearance of an ordinary air rifle.

In Fig. 5 a gun has been shown provided with a sight 25 which is reversible and can 35 be used as the means for discharging the projectable substance either forwardly or rearwardly while the barrel 7 is closed at its muzzle, it being unnecessary to use a valve with this form of device.

40 Having thus described the invention what is claimed is:—

1. A trick gun having a sight and provided with a front and a rear discharge, one of which is located in the gun sight.
2. A trick gun having a sight and provided with a forward and a rearward discharge passage, one of which is through the gun sight, and means for rendering either passage inoperative.
3. A trick gun having a sight and provided with a front and rear discharge passage, one of which is located in said sight, a closure, and a valve coöperating with the closure for controlling the discharge of a projectable substance through either passage.

4. A trick gun having a forward and a rearward discharge passage, both of which are located at the forward end of the gun, 60 and means for controlling the discharge of a projectable substance through either passage.

5. A trick gun including a false barrel provided with a chamber adapted to receive 65 a projectable substance, a true barrel dis-

posed within the false barrel and communicating with said chamber, a rearward discharge tube communicating with the interior of the true barrel, and a valve disposed within the false barrel for controlling the passage of the projectable substance to the said tube.

6. A trick gun having a chamber adapted to receive a projectable substance, a forward discharge passage communicating with said 75 chamber, a rearward discharge passage communicating with the forward discharge passage, and a valve mounted for rotation about the forward discharge passage for controlling the discharge of a projectable substance 80 through either passage.

7. A trick gun including a false barrel having a hollow sight and provided with a chamber adapted to receive a projectable substance, a true barrel communicating with 85 the chamber, and a valve mounted for rotation on the true barrel for controlling communication between the true barrel and the gun sight.

8. A trick gun including a false barrel 90 having a chamber adapted to receive a projectable substance, a true barrel disposed within the false barrel and communicating with said chamber, a hollow sight communicating with the interior of the true barrel, 95 and a valve mounted for rotation on the true barrel for controlling communication between the true barrel and the gun sight.

9. A trick gun including a false barrel provided with a chamber adapted to receive 100 a projectable substance, a true barrel communicating with the interior of the chamber and having its outer end threaded, a hollow gun sight communicating with the interior of the true barrel, a valve mounted 105 for rotation within the false barrel and having a longitudinal bore adapted to receive the true barrel, there being a port formed in said true barrel, a port formed in the valve and adapted to register with the port in the true barrel and sight, respectively, and a cap adapted to engage the threaded end of the true barrel when producing a rearward discharge.

10. A trick gun including a false barrel 115 having a chamber adapted to receive a projectable substance, a true barrel communicating with the chamber and having its outer end threaded, a removable closure adapted to engage said end, a hollow gun sight secured to the exterior wall of the false barrel, there being a port formed in the true barrel and disposed in alinement with one end of the sight, and a valve mounted for rotation within the false barrel and provided with a passage adapted to register with the port and sight, respectively.

11. A trick gun including a false barrel having a chamber adapted to receive a projectable substance, a true barrel communicat- 130

ing with the interior of the chamber and having its outer end threaded, a tube secured to the exterior wall of the false barrel and constituting a gun sight, the inner 5 end of said tube being provided with a port, a valve having a threaded bore for engagement with the threaded end of the true barrel and provided with a passage adapted to register with the port in the true barrel, 10 and gun sight, respectively, and a cap engaging the threads on the true barrel and adapted to bear against the valve.

12. A trick gun including a false barrel, a partition arranged within the barrel and 15 forming independent chambers, one of which is adapted to receive a projectable substance, a true barrel threaded in said partition and having its free end provided with a port and projected longitudinally 20 beyond the outer end of the false barrel, a rearward discharge tube secured to the exterior walls of the false barrel, said discharge tube constituting a gun sight and having its inner end provided with a port 25 communicating with one of said chambers, a

valve adjustable longitudinally of the true barrel and provided with a stop flange arranged to bear against the outer end of the false barrel, there being a passage formed in the valve and adapted to register with the 30 ports in the true barrel and gun sight, respectively, and a cap forming a closure for the outer end of the true barrel.

13. A trick gun having a sight provided with a discharge passage. 35

14. A trick gun having a sight provided with a rear discharge passage.

15. A trick gun having a chamber to receive a projectable substance, a forwardly extending barrel communicating with said 40 chamber, and a sight having a rear discharge passage communicating with the interior of said barrel.

In testimony that I claim the foregoing as my own, I have hereto affixed my signature 45 in the presence of two witnesses.
